UNITED STATES PATENT OFFICE.

BENJAMIN V. KERSHNER, OF BOSTON, MASSACHUSETTS, ASSIGNOR TO UNION SPECIAL MACHINE COMPANY, OF CHICAGO, ILLINOIS, A CORPORATION OF ILLINOIS.

LOOPER-THREAD-CONTROLLING MECHANISM FOR SEWING-MACHINES.

1,285,219.

Specification of Letters Patent Patented Nov. 19, 1918.

Application filed October 27, 1915. Serial No. 58,148.

To all whom it may concern:

Be it known that I, BENJAMIN V. KERSHNER, a citizen of the United States, residing at Boston, in the county of Suffolk, State 5 of Massachusetts, have invented certain new and useful Improvements in Looper-Thread-Controlling Mechanism for Sewing-Machines, of which the following is a description, reference being had to the accompanying drawing and to the figures of reference marked thereon.

This invention relates to new and useful improvements in looper thread controlling mechanisms for sewing machines, and more 15 particularly to the thread controlling mechanism wherein a rotating member takes up and releases the looper thread.

An object of the invention is to provide a looper thread controlling mechanism 20 wherein a rotating controlling cam co-operates with thread guides for taking up and releasing the looper thread, with an adjustable releasing finger for releasing the thread on the take-up cam and with an adjustable retaining finger for retaining the 25 thread after it is released, whereby the time of releasing and consequently the amount of thread taken up may be varied, and whereby the released thread may be retained 30 for a predetermined period of time.

In the drawings:

Figure 1 is a front view of a sewing machine having my improvements applied thereto, certain of the parts being broken 35 away and others removed in order to show the thread controlling mechanism;

Fig. 2 is a view, partly in plan and partly in section, showing a looper thread controlling mechanism, having my improvements applied thereto;

Fig. 3 is a vertical sectional view through the bed plate, showing in side elevation the controlling cam, the thread guides co-operating therewith, the take-up or releasing finger, and the check or retaining finger which 45 cooperates with said cam;

Fig. 4 is a detail in perspective showing the take-up finger and the retaining finger and the means for supporting the same;

Fig. 5 is a sectional view showing the manner of supporting the take-up finger,

also showing in side elevation the retaining finger;

Fig. 6 is a sectional view showing a modified form of means for supporting the take-up finger;

Fig. 7 is a view, partly in section and partly in side elevation, showing the take-up cam and the controlling fingers therefor, with the take-up cam in position for initial 60 engagement with the looper thread;

Fig. 8 is a similar view showing the take-up cam rotated to bring the looper thread into engagement with the take-up finger;

Fig. 9 is a similar view showing the looper 65 thread released from the take-up shoulder of the cam by said take-up or release finger, and the retaining or check finger as holding the thread; and

Fig. 10 is a similar view showing the take-up cam rotated so as to release the thread from said check or retaining finger.

In the drawings, I have shown my invention applied to a sewing machine consisting of a bed plate 1 having a standard 70 2 carrying an overhanging arm 3 in which reciprocates a needle bar 4 carrying a needle 5. The needle bar is reciprocated by a needle lever 6, pivoted at 7 to the overhanging arm, said needle lever being connected 75 80 by a link 8 to the needle bar. The needle lever is oscillated by a suitable eccentric on the main shaft, through an eccentric strap 9 pivoted at 10 to the needle lever.

Mounted on the bed plate 1 is a work support 11 having feed slots 12 through which the feed dog 13 operates. Coöperating with the needle beneath the work support is a looper 14, the looper being pivotally mounted on a looper support and moved into and 90 out of the needle loop by a link 15 which is pivoted at 16 to the needle lever extension 17.

The looper thread 1 is led from the supply through a suitable thread guide 18 and passed through a tension 19 to spaced thread 95 guides 20-20. Coöperating with the thread guides 20-20 is a suitable pull-off 21. After leaving the thread guides 20-20, the looper thread passes through nippers 22, and thence to the spaced thread guides 23-23. Coöperating with the spaced thread guides 23-23 is a rotating take-up cam 24 having the usual

central groove 25. The take-up cam 24 is mounted on the main shaft 26 and rotates therewith. The thread passes from the thread guide 23 at the left of the take-up 5 cam, as viewed in Fig. 2, to the looper 14.

Coöperating with the take-up cam 24 is a take-up finger 26'. This take-up finger 26' is mounted in a bracket 27 and extends outwardly from the bracket and thence downwardly into the groove 25 in the take-up 10 cam 24. The thread-engaging surface of the take-up cam 24 is provided with an eccentric shoulder *a* which coöperates with the take-up finger 26' to take up the looper 15 thread. The take-up cam rotates in the direction of the arrow in Fig. 3. In rear of the eccentric take-up shoulder is a concentric thread-engaging surface *b* which gives up the thread gradually, and thence an eccentric 20 surface *d* which gives up the thread very rapidly.

Also mounted on the bracket 27 is a retaining or check finger 28. As the cam 24 rotates, the cam shoulder *a* engages the 25 thread running through the thread guides 23 and carries the same along, as indicated in Fig. 8 of the drawings. The thread is brought into engagement with this take-up finger 26', and when the cam reaches the position shown in Fig. 9, the thread will be released from the cam shoulder *a* and will be caught by the check or retaining finger 28, as shown in this figure. A further rotation 30 of the cam brings the eccentric surface *c* underneath the retaining or check finger 28, and the looper thread will then be released so that it will be held solely by the eccentric surface *c* of the take-up cam. Further movement of the take-up cam releases the thread 40 from this surface *c* onto the surface *d* of the take-up cam.

The take-up finger 26' is carried by a shank 29, which extends downwardly through an opening 30 in the bracket 27. 45 A clamping screw 31 carried by the bracket is adapted to be set up against this shank and hold the take-up finger in an adjusted position. Viewing the parts as positioned in Fig. 9, it will be readily apparent that, if 50 this take-up finger 26' is raised, the point of releasing the thread will occur earlier in the time of rotation of the take-up cam 24, while, if the take-up finger is lowered, then the time of release will occur at a later period in the 55 rotation of the cam.

The check finger 28 has a downwardly extending shank 32 which is bent horizontally, forming a horizontal section 33. This horizontal section of the retaining or check 60 finger extends through an opening in the bracket 27, and a set-screw 34 carried by the bracket engages the shank and holds the retaining finger against movement. By loosening this screw, it will be apparent that 65 the retaining finger may be adjusted hori-

zontally so that the extreme end thereof, which coöperates with the take-up cam, may be moved either to the right or to the left, as viewed in Fig. 3.

When the thread is released from the cam 70 shoulder *a*, it will be caught by the retaining or check finger 28 and the amount of slack given up to the looper at this time, therefore, depends upon the distance between this retaining or check finger 28 and the cam shoulder when releasing the thread. By adjusting this retaining or check finger 28 to the right, as viewed in Fig. 9, more slack will be given to the thread, and by adjusting the same to the left, then less slack will 80 be given to the looper thread. It will be understood that in all positions of adjustment of the finger 28, the depending nose 28a thereof extends beneath the concentric surface *b* of the take-up cam 24.

In Fig. 6 of the drawings, I have shown a modified supporting means for the retaining finger. The shank 32 for the retaining finger 28 is vertical throughout and extends through an opening 35 in a support 36 carried by the bracket 27. This support has a threaded shank 37 carrying a threaded sleeve 38 which bears against the outer face of the bracket. There are two adjustable abutment screws 39 and 40 which are threaded 90 through the supporting bracket 27. By shifting the support through the turning of the sleeve 38, the shank of the same is clamped against these abutments 39 and 40. By shifting the position of the abutments 100 39 and 40, relative to each other, or relative to the shank, various adjustments of the retaining finger may be made so that said retaining finger may be shifted either to the right or to the left as viewed in Fig. 3, and 105 may also be slightly tilted so as to maintain the nose of the retaining finger a uniform distance beneath the concentric surface *b* of the take-up cam 24.

The operation of the needle and the looper 110 in this type of machine is well understood. The looper moves forward into the needle loop to the end of its stroke, after which it is shifted laterally and then retracted. The needle on its next descent passes between the 115 needle loop, the looper, and the looper thread, after which the looper is retracted from the previous needle loop, and the re-tracting movement of the looper, together with the downward movement of the needle 120 draws up the threads for the setting of the stitch. When the looper is at the forward end of its stroke, the take-up cam for the looper thread is substantially positioned, as shown in Fig. 7, and as the looper is retract- 125 ed this take-up cam engaging the looper thread, as shown in Fig. 8, takes up the slack in the looper thread caused by this backward movement of the looper. When the needle is near the lower end of its stroke and ready 130

to draw upon the threads to set the stitch, the take-up cam reaches the position shown in Fig. 9, at which point slack will be given to the looper thread to permit this setting of 5 the stitch.

In some machines, the needle bar is set so as to move to a higher point in order to obtain more clearance for the materials being sewed. This requires a shifting of the 10 position of the looper so that the point of the looper will pass the needle at a proper time. The shifting of the looper so that it moves to a greater distance away from the path of the needle requires that more slack 15 thread be given to the looper as it is reaching the rear end of its stroke. By adjusting the retaining or check finger 28, the amount of slack given to the looper thread may be regulated to correspond with the setting of 20 the looper. By my improved means of supporting the take-up finger, it may be quickly adjusted and set so as to properly coöperate with the take-up cam. By raising the take-up finger, the time of releasing the thread 25 will be slightly advanced, and by lowering the take-up finger, the time of release will be retarded. As soon as the thread is released from this eccentric surface α of the take-up cam, it is drawn against the re- 30 taining or check finger 28, and the position of this check finger determines the amount of slack given to the looper thread. By my improved means, therefore, of mounting the take-up finger and the retaining finger, I 35 am able to vary the time of release of the thread by the take-up finger, and the amount of slack retained by the retaining finger, so that the thread controlling mechanism may be quickly adjusted to properly operate on 40 the looper thread.

It is obvious that minor changes in the details of construction and the arrangement of parts may be made without departing from the spirit of the invention as set forth 45 in the appended claims.

Having thus described the invention, what is claimed as new and desired to secure by Letters-Patent is:—

1. The combination with a take-up cam, 50 a take-up finger for releasing the thread from the take-up cam, a retaining finger for retaining the thread when released from the take-up cam, means for supporting the take-up finger, whereby the same may be adjusted 55 for varying the time of release of the thread, and means for supporting the retaining fin-

ger, whereby the same may be adjusted independently of the take-up finger for varying the amount of slack in the thread held thereby.

2. The combination with a work support, 60 a needle, a thread-carrying looper coöperating with the needle beneath the work support, a looper thread controlling mechanism including thread guides, a rotating take-up cam having a thread-engaging shoulder for engaging the thread between said guides, a take-up finger for releasing the thread from the cam shoulder, a retaining finger for retaining the thread when released from the cam shoulder, and means for supporting the take-up finger whereby it may be adjusted 65 independently of the retaining finger.

3. The combination with a work support, 70 a needle, a thread-carrying looper coöperating with the needle beneath the work support, a looper thread controlling mechanism including thread guides, a rotating take-up cam having a thread-engaging shoulder for engaging the thread between said guides, a 75 take-up finger for releasing the thread from the cam shoulder, a retaining finger for retaining the thread when released from the cam shoulder, and means for supporting the retaining finger, whereby it may be adjusted 80 independently of said take-up finger.

4. The combination with a work support, 85 a needle, and a thread carrying looper coöperating with the needle beneath the work support, of a looper thread controlling 90 mechanism including thread guides for the looper thread, a rotating take-up cam for engaging the looper thread between said guides, said take-up cam having an eccentric thread engaging surface and a concentric thread engaging surface, a take-up finger coöperating with said take-up cam for releasing the looper thread from said eccentric surface, means for supporting the take-up finger whereby the same may be adjusted 95 100 for varying the time of release of the looper thread and means for supporting the retaining finger whereby the same may be adjusted independently of the take-up finger for varying the amount of slack in the looper 105 thread held thereby.

In testimony whereof, I affix my signature in the presence of two witnesses.

BENJAMIN V. KERSHNER.
